CLAIM

The ornamental design for a ridge vent, as shown and described.

DESCRIPTION

FIG. 1 is a front perspective view of a ridge vent, showing the new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a cross section view thereof taken along line 9-9 in FIG. 3 thereof; and,

FIG. 10 is an enlarged view of area 10 circumscribed in FIG. 9.

The evenly spaced broken line depict portions of the ridge vent and form no part of the claimed design. The long dash-short dash broken lines in FIGS. 9 and 10 denote the boundaries of the enlarged detail view and form no part of the claimed design.

The ridge vent is shown with a break in its length, the appearance of any portions of the article between the break lines forms no part of the claimed design.
